BOTTLE CLOSURE OR SIMILAR ARTICLE

Robert A. Roth, 15 E. 41st St., New York, N.Y. 10017

Filed Oct. 23, 1965, Ser. No. 87,855

Term of patent 14 years

(Cl. D58—26)

FIG.1

FIG.2

FIG.4

FIG.3

FIG.5

FIG. 1 is a perspective view of a bottle closure or similar article showing my new design wherein the top member is flat;

FIG. 2 is a sectional view taken on line 2—2 of FIG. 1, with a fragmentary showing of the top portion of a bottle in broken lines for illustrative purposes only;

FIG. 3 is a sectional view on line 3—3 of FIG. 2;

FIG. 4 is a fragmentary sectional view showing another form of my design wherein the top member is a shallow cone;

FIG. 5 is a fragmentary sectional view of another form of my new design wherein the top member is concave; and

FIG. 6 is an exploded perspective view of the closure shown in FIG. 1.

The essential features of the design are shown in full lines.

I claim:

The ornamental design for a bottle closure or similar article, as shown and described.
